land**

**Application December 14, 1936, Serial No. 115,886
In Great Britain February 27, 1936**

6 Claims. (Cl. 140—93)

This invention relates to the strapping of packages and other articles.

The invention has for object to provide improved apparatus relating to strapping with wire and other materials, the ends of which material are joined by twisting or other equivalent joint-forming operations, such as crushing or bending.

It is an object of the invention to provide a hand-operated strapping machine in which an oscillating member is operatively connected to carry out the twisting or other joint forming operation during both strokes of its oscillation.

It is a further object of the invention to provide a machine for making a twisted joint in which two or more twister pinions or the like are arranged for successive operation.

With these and other objects in view, the invention consists in the improved combinations and arrangements contained in the embodiments now to be described in detail, novel features of which are set out in the claims which follow.

In the drawings:—

Figure 1 is a front elevation, partly in section, of one form of machine, parts being broken away.

Figure 2 is a plan view of part of the same machine.

Figure 3 is a front sectional elevation of part of a modified form of machine,

Figure 4 is a plan view of the parts shown in Figure 3,

Figure 5 is a front elevation of the machine shown in Figures 3 and 4, and

Figures 6 and 7 show examples of the knots made by the machine of Figures 1 and 2 and Figures 3, 4 and 5 respectively.

The machine shown in Figures 1 and 2 is mounted on a base 1 and has right and left hand twisting pinions 2 and 3 respectively arranged to be operated by a common operating lever 4 through timing gears 5 and 6 which are mounted on a shaft 7. The shaft 7 is carried in bearings in members 8 and 9 upstanding from the base 1, and also has freely mounted upon it the operating lever 4. The timing gear 6 is freely mounted upon the shaft 7 whilst the timing gear 5 is keyed to the shaft as at 31.

The operating lever 4 carries spring-pressed clutch dogs 10 and 11 arranged to engage slots or recesses 40 and 41 formed in the inner faces of the gears 5 and 6 respectively; two such slots are formed in the face of each gear at diametrically opposed positions.

The slots 41 are so shaped that the timing gear 6 is positively engaged by the dog 11 for driving 55 during the forward stroke of the lever 4, but that

the dog slips out of the slot and comes to ride on the face of the gear during the backward stroke. The slots 40 are shaped so that the gear 5, pinion 2 and the shaft 7 are driven on the backward stroke of the lever 7 but remain idle during the forward stroke.

Since there are two diametrically arranged slots in each gear, the dog which has been riding on the face of the respective gear during any particular stroke of the handle 4 slips into a slot at the end of the stroke ready to take up the drive during the next stroke.

Spring-pressed plungers 42 and 43 carried by the members 8 and 9, are provided to engage diametrically opposed holes 44 in the faces of the gears 5 and 6 to hold them against rotation except when positively driven by the lever 4.

In addition to the parts already mentioned, the machine comprises means for locating and retaining the wire during the operation of the machine, means for tensioning the wire about the article to be strapped and means for cutting off the end of the wire, as will appear below.

In the use of the machine, the end of a length of wire, drawn, preferably, from a coil, is passed between a pivoted spring-pressed wire-gripper 13 and the associated anvil 14, to abut against a stop-plate 15 and is gripped by the gripper 13. Its end having thus been located and anchored the wire is inserted in the slots of the twister pinions 2 and 3 and in the holding slot 16, and is passed round the article which is to be strapped; the portion which then runs across the top of the article from left to right as seen in the drawings, and leads to the free end, or the coil as the case may be, is inserted in the slots of the twister pinions and the holding slot 16, to lie against the bight of wire already in these slots, and between the pivoted spring-pressed wire-grippers 17 and 18 and their associated anvils 19 and 20. A pivoted wire-retaining latch 21 is provided to retain the wire in position during the operation of the machine.

It will be seen from the drawings that the distance separating the pinions 2 and 3 is twice that separating each pinion from the nearest wire holding means, that is between the pinion 3 and the holding slot 16 and between the pinion 2 and the adjacent edge of the anvil 14; moreover no provision is made for holding the wire between the two pinions.

The gripper 18 forms part of the wire-tensioning mechanism and is carried by a member 23 which is slidably mounted on a shaft 24. The member 23 is formed with a helical cam-face 26

and a similar cam-face 27 of opposite hand is formed on a fixed member 28 on which the gripper 17 is pivotally mounted. A member 29, having an operating handle 30, is mounted on the 5 shaft 24 between the cam faces 26 and 27 and itself has cam faces 31 and 32 for co-operating with these cam faces. A spring 33 mounted on the shaft 24 between the slideable member 23 and a plate 34 tends to urge the member 23 towards the left and to maintain engagement between the 10 respective cam faces.

It will be seen from Figure 1 that the pivoted grippers 17 and 18 are self-locking to prevent relative movement of the wire in one direction, 15 that is from right to left as seen in the drawings, but will automatically pivot to allow relative movement in the other direction. Thus when the tensioning handle 30 is rotated about the axis of the shaft 24, the cam action of the faces 26 and 31 and 27 and 32 respectively causes the gripper 18 to move to the right, drawing with it the wire which slides between the gripper 17 and anvil 19. Upon the return stroke of the handle 20 30, the member 23 is returned toward the left by its spring 33, the gripper 18 sliding over the wire, which is held by the gripper 17, to grip it in a fresh place ready for the next operative stroke of the handle 30. The tensioning of the wire about the article can be continued, by repeated 25 strokes of the handle 30, until the desired tension is obtained, this being determined either by the operator or by an automatic clutch inserted between the member 23 and its operating handle 30.

When the tensioning of the wire has been completed, 30 the operator effects the forward stroke of the lever 4, during which the pinion 3 is rotated by the timing gear 6, rotating freely on its shaft 7. This rotation of the pinion 3 results in the two bights of wire which pass through its slot 35 being twisted about each other twice between the pinion 3 and the slot 16 and twice, in the opposite sense, between the two pinions 2 and 3, there being, as shown, a 4:1 reduction ratio between the timing gears and the pinions. Upon the completion 40 of the forward stroke of the lever 4, the operator reverses its direction and effects the return stroke, during which the gear 5 and the shaft 7 are rotated in the reverse direction. This rotation results in the pinion 2 being rotated in 45 the direction opposite to that in which the pinion 3 was rotated and the two bights of wire are twisted about each other twice between the pinion 2 and the edge of the anvil 14, these twists being in the same sense as those previously formed between the pinion 3 and the slot 16. During this 50 rotation of the pinion 2 two further twists are formed in the wire between the two pinions, these twists being in the same sense as those previously formed in these portions of the bights of wire. 55 The completed knot thus has four twists in the same sense, situated between two sets of two twists each in the opposite sense, all the twists being of approximately the same pitch.

During the rotation of the timing gear 5, the 60 rotation of the shaft 7, which is keyed to it, causes the operation of a wire-severing device 35 which is arranged to sever the outer bight only, that is the bight leading to the free end or to the coil. The wire severing device is operated 65 through a cam 45 keyed to the shaft 7.

From the above description it will be seen that 70 the end part of the knot remote from the anchored end is first completed (by rotation of the pinion 3) and the wire is severed near this completed portion of the knot during the formation 75

of the other end part of the knot. This prevents any weakness resulting from the neck of the wire behind the cut being twisted on its own axis when the cut off end is free.

Other advantageous features of the machine 5 just described concern the prevention of wastage, especially when wire from a coil is used.

The use of stop-plate 15 enables the end of each length of wire to be located and thus determines the correct length of wire for each operation. 10

Owing to the slope of the surface of the anvil 14, the anchored end of the wire is pushed down when tension is applied and no wire need be cut off at this end to make a neat joint. 15

During tensioning, wire is fed back toward the coil in a straight path and is cut off (being thereby tucked down sufficiently) close to the end of the joint. There is thus no waste of wire, whatever, since the severed end of the wire from the 20 coil forms the end of the next loop which is pushed against the stop-plate 15.

Figures 3, 4 and 5 illustrate a machine having but one twister pinion and designed to produce a joint comprising two sets of three twists each in 25 opposite senses. In this machine, the devices provided for gripping, locating, retaining and stretching the wire are similar to those of the machine illustrated by Figures 1 and 2, and, while such parts are omitted from Figures 3 and 4, 30 they appear in Figure 5 and in such Figure 5 are designated by the same reference numerals as similar parts in Figure 1.

The twister pinion 2 is in driving engagement with a timing gear 51 which is mounted for 35 rotation about the axis of a shaft 7, borne in bearings in members 8 and 9 upstanding from the base 1.

The timing gear 51 is mounted upon and keyed at 64 to a collar 65 of a bevel wheel 54 which is 40 keyed to the shaft 7 at 62. A further bevel wheel 55 is loosely mounted on the shaft 7, and both bevel wheels 54 and 55 engage a small idler bevel wheel 56, the vertical spindle 57 of which is borne in a portion 58 upstanding from the 45 base 1.

An operating lever 4 is freely mounted upon the shaft 7, by a portion 59 which extends between the bevel wheels 54 and 55. The lever 4 carries a pair of pivoted spring-pressed dogs 60 50 and 61, which are arranged to engage slots or recesses in the peripheral surfaces of the bevel wheels 54 and 55 respectively. These dogs are so formed that, during the forward stroke of the lever 4 from the position shown in plan in 55 Figure 2, the dog 61 drives the bevel wheel 55 through positive engagement with the slot in that wheel, whilst the dog 60 slides out of the slot in the wheel 54, depressing its spring, and rides over the surface at the wheel which is driven through the train 55, 56 and transmits drive to the timing gear 51 through the key 64.

The directions of rotation of the wheels 54 and 55 are opposed, so that, at the conclusion of the forward stroke of 180° revolution of the lever 65 4, the dog 60 again slips into the slot which it left at the beginning of the stroke. During the return stroke of the lever 4, owing to the shape of the dogs, the dog 60 drives the wheel 54 through positive engagement with the associated slot, 70 whilst the dog 61 leaves the slot which it had previously engaged and slides over the peripheral surface of the wheel 55 to engage the slot again at the completion of the stroke.

Owing to the alternate driving engagement of 75

the lever 4 with the bevel wheels and the provision of the idler wheel 56, the direction of rotation of the timing gear, and thus of the twisting pinion 2, is constant.

5 The shaft 7 is also driven in constant direction and operates wire-severing mechanism by means of a cam 45 keyed to the shaft.

A spring-pressed plunger 42 is provided in the member 8 to co-operate with a hole 44 in the 10 timing gear 51 to locate the latter at the completion of the return stroke of the operating lever.

I claim:—

1. A hand-operated strapping machine comprising an oscillating lever or the like, a twisting pinion, unidirectional clutches for connecting said oscillating lever or the like to said twisting pinion during oscillation in either direction, and reversing gearing through which said oscillating lever or the like is connected to said twisting pinion during oscillation in one direction.

2. A hand-operated strapping machine comprising an oscillating member, a twisting pinion, reversing gearing comprising a pair of bevel wheels and a common idle bevel wheel, and unidirectional clutches whereby said oscillating member is connected to said twisting pinion during oscillation in either direction, the connection during oscillation in one direction being through said reversing gearing.

3. A hand-operated strapping machine comprising a twisting pinion, an oscillating member, and mechanism whereby said oscillating member is operatively connected to said twisting pinion to rotate it in the same direction during oscillation of said member in either direction.

4. A hand-operated strapping machine comprising an oscillating lever, a twisting pinion, a gear wheel meshing with said twisting pinion, a unidirectional clutch device for connecting said oscillating lever to said gear wheel to rotate it during oscillation in one direction, reversing gearing, and a second unidirectional clutch device for connecting said oscillating lever to said twisting pinion through said reversing gearing during oscillation in the other direction.

5

10

5. A hand-operated strapping machine comprising an oscillating member, a twisting pinion, reversing gearing comprising a pair of toothed wheels and a common idle wheel meshing with said pair of toothed wheels, a unidirectional clutch device for connecting said oscillating member to said twisting pinion during oscillation in one direction, and a second unidirectional clutch device for connecting said oscillating member to said twisting pinion during oscillation in the other direction, the connection of said oscillating member to said twisting pinion during oscillation in one direction being through said reversing gearing.

15

6. A hand-operated strapping machine comprising a twisting pinion, an oscillating member, means for connecting said oscillating member to said twisting pinion during oscillation in one direction to rotate it in a certain direction, and means for connecting said oscillating member to said twisting pinion during oscillation in the opposite direction to rotate it in the said certain direction.
